(57) **CLAIM**

The ornamental design for a computing device, as shown and described.

DESCRIPTION

FIG. 1 is a right side perspective view of a computing device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The even-length broken lines in the drawings illustrate portions of the computing device that form no part of the claimed design. The dash-dot-dash lines in FIGS. 1-6 and 8 represent a claim boundary and form no part of the claimed design.
